CLAIM

The ornamental design for a drinking cup, as shown and described.

DESCRIPTION

FIG. 1 is a perspective view of a first embodiment of a drinking cup showing our new design;
 FIG. 2 is a front view of the drinking cup of FIG. 1;
 FIG. 3 is a side view of the drinking cup of FIG. 1;
 FIG. 4 is a bottom view of the drinking cup of FIG. 1;
 FIG. 5 is a top view of the drinking cup of FIG. 1;
 FIG. 6 is a perspective view of a second embodiment of a drinking cup;
 FIG. 7 is a front view of the drinking cup of FIG. 6;
 FIG. 8 is a side view of the drinking cup of FIG. 6;
 FIG. 9 is a bottom view of the drinking cup of FIG. 6; and,
 FIG. 10 is a top view of the drinking cup of FIG. 6.
 The broken lines in the Figures are included for the purpose of illustrating portions of the drinking cup that form no part of the claimed design.
